of Delaware

Application December 23, 1954, Serial No. 477,319

Claims priority, application Netherlands January 11, 1954

7 Claims. (Cl. 179—18)

The invention relates to an electrical identification system and more particularly to one which can cause a code recording to be made characterizing the presence of a signalling condition on one out of a plurality of individual points.

Such identification problems are frequently met in telephone systems and for example in relation to the detection and the identification of a calling condition on a subscriber's line. In this respect, it is already known to use a common call detector which will produce a signal when a calling condition has arisen for one line out of a group and as a result thereof to start a rotating switch serving that group until the latter arrives in a position corresponding to the calling line, the physical position of the switch wipers permitting identification of the calling line. This switch might of course, be a line finder and in that case all that is required is that it should be positioned on the calling line. When crossbar switches are used as line finders, it is not desirable to make them hunt for a calling condition on one of the lines to which they have access, since this would take an unduly long time. A separate identifying arrangement is then required and such an arrangement has been described, for example, in the application of W. Pouliart et al., Serial No. 167,752, filed June 13, 1950. In this patent, a switch which is actually an electronic scanning arrangement continuously scans a group of lines and effects temporary but continuously repeated connections with each line during particular time intervals within a cycle each of which identifies a particular line, so that whenever a calling condition arises, this can be detected within the cycle period and at the same time the identity of the calling line can also be registered. If M is the number of lines forming a group and T the time necessary for the scanner to move from one line to the next, a maximum time MT will be required to detect and identify a calling line. If the number of lines in a group is appreciable, e.g. $M=100$, T should be rather small if a calling line is to be detected and identified within a short period of time, e.g. less than half a second. In the above mentioned application, T was made quite small by using a pulse controlled electronic scanner.

The object of this invention is to permit an immediate detection of the appearance of a signalling condition at one individual point out of a plurality, together with a rapid identification of this individual point and within a maximum time which instead of being proportional to the total number of individual points is proportional to an appreciably smaller number.

In accordance with a characteristic of the invention an electrical identification system is provided comprising a plurality of points which are to be identified and a common point connected to each of the individual points via gates arranged in stages. There are a plurality of gates at the first stage all connected to the common point and each connected in turn to a different set of gates at the second stage, each gate of a set being in turn con-

2

nected to a different set of gates at the next stage. This arrangement is repeated, until at the last stage there is a gate for each individual point to be identified.

There may be said to be $M_1 \times M_2 \times \dots \times M_{n-1} \times M_n$ individual points, where $M_1, M_2, \dots, M_{n-1}, M_n$ are the respective numbers of the gates in each set at the stages 1, 2, ..., $n-1$, and n , n being greater than 1. The gates of each set of gates at a stage are individually controlled from a corresponding set of control points, corresponding gates of each set of a stage being controlled from the same one of the control points of the corresponding set. For example, the individual gates M_1 of the first stage are respectively controlled from control points M_1 ; the individual gates $M_1 \times M_2$ at the second stage have corresponding gates of each set M_2 controlled respectively from the control points M_2 , and so on for successive stages, until the individual gates, $M_1 \times M_2 \times \dots \times M_{n-1} \times M_n$ of the last stage have corresponding gates of each set M_n of the $M_1 \times M_2 \times \dots \times M_{n-1}$ sets controlled respectively from the control points M_n .

A detector is connected to said common point and reacts upon a signal being able to reach it from any of said individual points with the characteristic that a series of n multi-stable electrical devices having respectively at least $M_1, M_2, \dots, M_{n-1}, M_n$ stable positions are provided, one for each set of control points at each stage. A first electrical condition is normally applied to all the control points which makes all gates unidirectionally conductive all in the same sense with respect to said common point, whereby a signalling condition at one or more of the individual points will actuate the detector. Means are provided as a result thereof to cause a second electrical condition to be applied to all the gates at one stage which makes them non-conductive, whereby the detector releases. Means are provided as a result thereof to cause the multistable device corresponding to the stage of non-conductive gates to be successively driven from one of its stable conditions to the next, resulting in the separate application of said first electrical condition to each successive control point at said stage until the detector is again actuated. Means are provided to cause said multi-stable device to remain in the position which permitted the detector to be actuated and to cause said second electrical condition to be applied to all the gates at another stage, whereby these gates become non-conductive and the detector is again released with corresponding results, these operations being continued until the last of said multi-stable devices is set into the position which permits the detector to be actuated, whereby the various positions of the n devices indicate the identity of an individual point at which a signalling condition was originated, the disappearance of said signalling condition causing the release of the detector which in turn causes said first electrical condition to be again applied to all control points.

The above mentioned and other objects and characteristics of the invention will be better understood from the following description of an embodiment to be read in relation with the accompanying drawings in which:

Fig. 1 represents the identification equipment necessary for identifying a calling telephone line out of a group of one hundred lines, and

Fig. 2 is a detailed circuit of the input connection to the tube VA of Fig. 1.

The system is adapted to react to voltage variations in the line circuit so that relayless line circuits can be used. As shown, the "a" wire of the subscriber's line is connected to ground through a resistor of 15 kilo-ohms while the "b" wire is connected to the negative pole of a 48 volt battery through a resistor of 30 kilo-ohms. The "b" wire is also connected to the control grid of a triode

VA through a resistor of 30 kilo-ohms in series with three rectifiers S_1 , S_2 , S_3 . This control grid is connected to -48 volts through a resistor of 250 kilo-ohms. The anode of VA is connected to ground through the winding of a relay Tr , while the cathode is connected to ground through a resistor of 10 kilo-ohms and to -48 volts through a resistor of 1 kilo-ohm. When the subscriber's line is open, the potential at the "b" wire is -48 volts and such a potential is also present at the control grid of VA, whereby, owing to the higher potential at the cathode of VA, this tube is non-conductive and relay Tr is at rest. When the subscriber's loop is closed as a result of a call, the potential on the "b" wire becomes substantially equal to -16 volts, the rectifiers S_1 , S_2 , S_3 are made conductive, and the corresponding increase of potential at the grid of VA causes the tube to conduct, whereby Tr operates.

The numbered arrows at the control grid of VA, the junction point of S_3 and S_2 , the junction point of S_2 and S_1 , indicate that these respective points are each multiplied to a corresponding number of circuits, there being 4 rectifiers such as S_3 , 4×5 rectifiers such as S_2 , and $4 \times 5 \times 5$ rectifiers such as S_1 . A more detailed disclosure of this circuit is shown in Fig. 2 where the four rectifiers S_3 are shown with one of these rectifiers connected to five of the S_2 rectifiers each of which is shown connected to five of the S_1 rectifiers. The S_1 rectifiers are each connected through an S_4 rectifier to a contact of one of the relays Aa to Ae which lead to the make contact Ha_4 , the armature of which is connected to negative battery. Each of the lines leading from S_1 rectifiers go to a line circuit through the resistor shown in Fig. 1, but omitted in Fig. 2. With this arrangement, the grid of VA is normally coupled to a hundred line circuits, such as the one shown, and the rectifiers serve to decouple the various line circuits from one another.

Via contact t of relay Tr in the make position, relay Har is energized through its break contact Ha_2 . This relay locks to ground through make contact Ha_1 and break contact K_1 of relay Kr . As a result of the operation of relay Har , -48 volts is now connected through make contact Ha_4 to a set of five contacts Aa_0-e_0 associated respectively with the relays $Aar-Aer$. Each of these last contacts is connected to the cathode of twenty rectifiers, such as S_4 , the anodes of which are connected to the c wires of the hundred line circuits. This means that the potential of -16 volts which had appeared on the c wire of the calling line circuit will now be replaced by -48 volts whereby the tube VA will no longer be conductive and relay Tr will release. Relay Tr is a fast releasing relay, so that relay Hbr has no opportunity to energize through make contact Ha_2 .

The release of relay Tr causes the operation of relay Aar through break contacts Ae_3 , Aa_2 , Ab_3 , Ac_3 , Ad_3 , make contact Ha_3 and break contacts Hb_4 and t . Relay Aar locks through make contact Aa_1 , break contacts Ab_2 , Ac_2 , Ad_2 , Ae_2 and K_1 . If the calling line is in the group of 20 lines which corresponds to relay Aar , due to the opening of contact Aa_0 , a potential of -16 volts will again be able to reach the grid of tube VA whereby relay Tr will again operate. This will result in relay Hbr being energized through make contacts t and Ha_2 and break contact Hb_2 . Relay Hbr locks through make contact Hb_1 and break contact K_1 .

If the calling line was not included in the group of 20 lines corresponding to relay Aar , relay Tr would not have been operated upon the energization of relay Aar and the latter operation would have permitted the subsequent operation of relay Abr through make contact Aa_2 , break contacts Ab_3 , Ac_3 , Ad_3 , make contact Ha_3 and break contacts Hb_4 and t . Relay Abr would have locked through make contact Ab_1 , break contacts Ac_2 , Ad_2 , Ae_2 and K_1 and caused the release of relay Aar at break contact Ab_2 . If the calling line had been in the group of 20 lines corresponding to relay Abr , then the opening of

contact Ab_0 would have resulted in the operation of relay Tr and the subsequent operation of relay Hbr in exactly the same way as described above. It will be clear that if relay Tr does not operate as a result of the operation of relay Abr , then relay Acr will be energized while relay Abr will be released, and so on until relay Tr responds. It should be observed that relay Tr is also a fast operating relay, whereby it energizes so quickly that there is no possibility for the following code relay to be operated, so that when relay Tr responds after the energization of relay Aar , relay Abr will have no opportunity to energize and out of the five relays $Aar-Aer$, relay Aar will be the only one to be and remain energized.

15 The operation of relay Hbr will cause -48 volts to be applied through make contacts Ha_5 to five contacts Ba_0-e_0 , each of which is connected to the cathodes of four rectifiers such as S_5 , the anodes of which are individually connected to the junction points of rectifiers such as S_1 and S_2 . It is clear that this connection will again re-establish a potential of -48 volts at the grid of tube VA whereby relay Tr will again release, and, as a consequence, relay Bar will be energized through break contacts Be_3 , Ba_2 , Bb_3 , Bc_3 , Bd_3 , make contact Hb_3 and break contacts Hc_2 and t , in a way exactly similar to that in which relay Aar was operated. The opening of contact Ba_0 will suppress the potential of -48 volts connected to the cathodes of four rectifiers such as S_5 , and if the anode of one of these rectifiers happens to be connected to the c wire of the calling line through a rectifier such as S_1 , a potential of -16 volts will again be able to reach the grid of tube VA, whereby relay Tr will again operate. If not, relay Bbr will be operated while relay Bar will be released, and so on until relay Tr is energized, whereby the last relay of the B group which was energized will remain locked in a manner similar to that described in connection with relay Aar .

Since relay Hbr , as well as relay Har , are now operated, the renewed energization of relay Tr will produce 40 the operation of relay Hcr through make contacts t , Ha_2 , Hb_2 and break contact Hc_2 , and this relay will lock through make contact Hc_1 and break contact K_1 . Again, the potential of -16 volts at the grid of tube VA will be suppressed, this time due to the closure of make contact Hc_5 leading to the contacts ca_0-d_0 and the rectifiers, such as S_6 . Relay Tr will again release, and this will result in the successive energizations of the relays of the C group until relay Tr is again operated.

At this moment, one relay in each of the A, B, and C 50 groups is energized and the operated combination characterizes the identity of the calling line in a non-ambiguous manner. It can easily be verified that in the event of simultaneous calls, there will be no mixing of codes.

55 The code used is of the form $1C_5\ 1C_5\ 1C_4$ which means that a hundred different combinations each of which characterizes a particular line can be obtained with fourteen elements, which for a hundred different combinations represents the smallest number of elements for any code with a constant number of operated elements, i.e. 3 in this case.

When relay Tr again operates after relay Hcr has 60 operated, this will cause the operation of relay Hdr through make contacts t , Ha_2 , Hb_2 and Hc_2 . This operation can now be used in any desired manner (not shown) to initiate the selection of a line finder having access to the group of the calling line and which can then be set on this line. It will be assumed that the line finders are arranged in groups forming a multi-switch 65 of the type disclosed in the application of J. Kruithof et al., Serial No. 280,252, filed April 3, 1952. The multi-switch is of the crossbar type, has a plurality of inlets and a hundred outlets and comprises a first set of 25 select bars plus a second set of 2 auxiliary select bars. 70 By operating one select bar out of each set, a selection of

one out of fifty outlets can be accomplished. When access to a suitable multi-switch has been obtained by means not shown, make contact Hd_2 will apply ground to the pyramid contact arrangement shown in the figures. If it is assumed that relays Aar , Bar and Car have been operated and therefore identify the calling line, ground will be applied through make contacts Ba_3 and Aa_3 to the electro magnet VM_1 which is one out of the 25 corresponding to the 25 select bars. Owing to the mechanical arrangement, the contact V will be closed as a result of the displacement of the select bar corresponding to the electromagnet VM_1 , as it would in response to the displacement of any select bar out of the first set.

Therefore, through make contacts V and Ca_3 , a ground will be applied to the electromagnet VM_{26} which is one out of the two controlling the two auxiliary select bars, and this electromagnet will also be operated.

At this moment, both the electromagnets VM_1 and VM_{26} being operated, the corresponding select bar and auxiliary select bar are displaced and the displacement of the actuating and hold bar corresponding to the seized individual line finder part of the multi-switch will effect through-connection to the line circuit of the calling line, but since a selection of one out of fifty only has been made, there still remains a selection of one out of two to be made which is accomplished, as explained in the above mentioned application, Serial No. 280,252, by displacing the actuating and hold bar in one sense or in the other.

Each of the actuating and hold bars corresponding to an individual line finder is provided with a hold magnet of which a contact H is shown. This hold magnet will be energized as soon as the select bars have been displaced and as a result, ground will be applied through make contacts H and Ca_4 to the electromagnet SH_1 . As explained in the above mentioned application, Serial No. 280,252, this electromagnet is one out of two which is used to perform the actual displacement of an actuating and hold bar of which the hold magnet has been operated. The operation of SH_1 will result in the actuating and hold bar being displaced in one sense, while the operation of SH_2 would result in the bar being displaced in the opposite sense, so that finally a selection of one out of a hundred will be accomplished.

As soon as a line finder is connected to the line circuit of the calling line of which the identity is registered in the circuit shown on the figure, a potential of -48 volts will be applied through the line finder to the c wire of the calling line, whereby relay Tr will again release. The release of relay Tr will now cause ground to be applied through break contact t and make contact Hd_1 to relay Kr which will be energized, whereby all attracted relays will be released due to the temporary opening of contact K_1 . Both relays Hd_1 and Kr should be relatively slow-releasing, the first to permit the temporary energization of the second and the second to permit the release of all other operated relays. The identification circuit is therefore fully released and ready to identify a new calling line. If several lines had been calling simultaneously, one would have received preference for being identified in view of the cyclic scanning arrangement in stages, but as soon as all relays have released in the manner explained, relay Tr will immediately reoperate and the identification of the next line will be made.

If for some reason the line loop is opened while the scanning operation is in progress in any one group, relay Tr cannot operate or must release and the next relays in the group operate in turn until the last one energizes. If it is assumed that the line loop is opened while the sequential operation of the relays of the A group are taking place, relay Aer will finally operate and ground will be applied to relay Kr through break contacts t , Hb_4 , make contact Ha_3 , break contacts Ad_3 , Ac_3 , Ab_3 , Aa_2 and make contact Ae_3 to cause the energization of

relay Kr . As explained in connection with the normal release, the operation of relay Kr will put the circuit back to normal. It should also be remarked that if due to some faulty condition, relay Tr fails to attract at the proper moment with sufficient speed, the last relay of a group will finally be operated with the same results as in the case of a premature release. The release of the circuit will also take place if the subscriber hangs up after relay Hd_1 has been operated.

10 Although an embodiment of the identification of a calling line has been described, it will be understood that the same circuit might be used to select a free outlet within a group of marked outlets of a group selector switch, or in the case of a final selector, to identify a line to which a connection is wanted and to which a marking potential is applied.

15 The electrical identification system described can be used to identify any electrical circuits out of a group. It may also be observed that although relay counters 20 have been shown, other kinds of elements could be used, such as gas discharge tubes or other electric, electronic or magnetic devices. As other electro-mechanical elements, step-by-step switches could be used, e.g. with a code $1C_{10} 1C_{10}$ two step-by-step switches having at least 25 ten positions, and a number of wipers depending on the code used for the control of a crossbar switch, would be necessary.

25 While the principles of the invention have been described above in connection with specific apparatus, it 30 is to be clearly understood that this description is made only by way of example and not as a limitation on the scope of the invention.

What is claimed is:

35 1. Electrical identification system, comprising a common detector connected to each of a plurality of individual points which are divided in n ($n > 1$) different ways into M_1 , M_2 . . . M_n groups, where $M_1 \times M_2 \times \dots \times M_n$ equals the total number of said plurality of individual points, a plurality of $M_1 + M_2 + \dots + M_n$ means, one 40 for each group, for disabling the connection between said individual points and said common detector, means responsive to a signal received by said detector for controlling said disabling means, whereby during absence of a signalling condition on said individual points none of the disabling means are effective, means in said control means 45 responsive to a signalling condition being detected on any one or more of said points for operating said control means to cause said disabling means successively to perform n selections, during each of which all but one out of M_1 , M_2 . . . M_n groups of individual points are successively excluded from access to the common detector.

50 2. Electrical identification system, according to claim 1, further comprising means in said disabling means operable during each of said n selections to give access to successive groups in a time sequential order until a group is reached in which a signalling condition exists, and means responsive to said common detector for stopping the action of said disabling means when a signal is received by said detector.

55 3. Electrical identification system, according to claim 2, in which the means in the disabling means for giving access to successive groups of individual points is adapted to eliminate all but one out of M_1 groups for the rest of the selecting process during the first of the n selection and to repeat this elimination process for the remaining points during each of the following $n-1$ selections until one only of said plurality of points remains effectively connected to the common detector.

60 4. Electrical identification system, according to claim 3, in which the control means comprise n multistable devices having respectively at least M_1 , M_2 . . . M_n stable conditions, one such device being operated during each selection.

65 5. Electrical identification system, according to claim 4, further comprising means in the control means for

driving each multistable device during its operation sequentially through its stable conditions, and means operable in each of these stable conditions for giving one group access to the common detector to the exclusion of all other groups, until a group is found, in which a signalling condition exists.

6. Electrical identification system, according to claim 3, further comprising means for restoring said control means upon removal of the signalling condition from the selected point.

7. Electrical identification system comprising a plurality of individual points, a common point, a plurality of gates, means including said gates for connecting said common point to each of said individual points, said gates being arranged in stages, each stage having a plurality of gates, the gates of the stages beyond the first stage being arranged in sets with the gates of each set being connected to a particular gate of the preceding stage which is different from the gates to which the other sets are connected and to all the gates of a set in the next succeeding stage, a plurality of control points for each stage, there being as many control points in each stage as there are sets of gates in that stage, means for controlling corresponding gates in the sets of each stage from respective control points associated with that stage, a detector connected to said common point and responsive to a signal received from any of said individual points, a multistable electrical device associated with each stage having at least as many stable conditions as there are control points at each stage, means for normally applying a first electrical condition to all said control points, means responsive to said first electrical condition for making all gates unidirectionally conductive, all in the same sense with respect to said common point, whereby a signalling condition at one or more of the individual points will actuate the detector, means responsive to the said

actuating of said detector for applying a second electrical condition to all the gates at one stage, said means responsive to said first electrical condition also being responsive to said second electrical condition for making the gates at said one stage non-conductive, whereby the detector releases, means responsive to the release of said detector for causing the multistable device corresponding to the stage of non-conductive gates to change successively from each of its stable conditions to the next, thereby applying said first electrical condition separately to each successive control point at said stage until the detector is again actuated, and means responsive to a succeeding operation of said detector for causing said multistable device to remain in the position which permitted the detector to be actuated and for causing said second electrical condition to be applied to all the gates at another stage, whereby these gates become non-conductive and the detector is again released with corresponding results, these operations being continued until the last of said multistable devices is set into the position which permits the detector to be actuated, whereby the various positions of said multistable devices indicate the identity of an individual point at which a signalling condition was originated, the disappearance of said signalling condition causing the release of said detector which in turn causes said first electrical condition to be again applied to all control points.
